[57] CLAIM

The ornamental design for a serving tray, as shown and described.

DESCRIPTION

FIG. 1 is a top perspective view of a serving tray, showing my new design;

FIG. 2 is a side elevational view thereof taken in the direction of line II on FIG. 1;

FIG. 3 is a front elevational view thereof taken in the direction of line III on FIG. 1;

FIG. 4 is a top plan view thereof;

FIG. 5 is a bottom plan view thereof.

The side view opposite that shown in FIG. 2 is similar thereto and the rear view opposite the front view shown in FIG. 3 is similar thereto.
